UNITED STATES PATENT OFFICE.

JOHN STOGDELL STOKES, OF MOORESTOWN, NEW JERSEY, ASSIGNOR TO STOKES & SMITH COMPANY, OF SUMMERDALE, PENNSYLVANIA, A CORPORATION OF PENNSYLVANIA.

SEALED WRAPPED PACKAGE AND OPENER THEREFOR.

1,154,217.

Specification of Letters Patent. Patented Sept. 21, 1915.

Application filed August 9, 1915. Serial No. 44,463.

To all whom it may concern:

Be it known that I, JOHN STOGDELL STOKES, a citizen of the United States, residing at Moorestown, in the county of Burlington and State of New Jersey, have invented new and useful Improvements in Sealed Wrapped Packages and Openers Therefor, of which the following is a specification.

10 My present invention relates to certain new and useful improvements in sealed wrapped packages of merchandise, such for instance as packages of cakes, crackers, biscuits, cereals, candies, and other commodities which are usually packed in boxes and the latter then inclosed within a wrapper which seals the box against the entrance of air, moisture and vermin.

The principal object of the invention is to 20 provide such packages with an opening device designed, upon withdrawal thereof from the package, to cut or tear the wrapper sufficiently to enable the lid or cover flap of the box to be opened, and the presence of 25 which opening device does not in any way affect or prevent the complete sealing function of the wrapper.

I am aware that it is not broadly new, so 30 far as the patented art is concerned, to provide envelopes, as well as wrapped packages, with an opening device adapted upon withdrawal to tear or cut the envelop or wrapper, but in all such packages or envelopes, so far as I am aware, the opening device has 35 a grasping portion that projects through an opening in the wrapper or envelop. Such proposed devices have therefore never gone into general use because the opening in the wrapper left for the grasping portion of 40 the opening device not only very materially affects the much desired "seal"; but such grasping portions which are usually in the form of tongues or tabs and which are usually free, are often accidentally pulled or 45 dislodged in handling and packing the packages resulting in the wrapper becoming prematurely torn and the seal further broken.

The aim of the present invention is to 50 obviate the aforesaid and other objections present in prior proposed wrapped packages and to provide a thoroughly and effectively sealed wrapped package having an opening device associated therewith which leaves no

opening in the wrapper and which has no projecting tabs or tongues, but which nevertheless is readily accessible for the purpose of opening the package.

Briefly and generally stated, the invention comprises a sealed wrapped package embodying a box or container, and a wrapper 60 completely enveloping all the exterior walls thereof and sealing the same, combined with a wrapper severing device completely enclosed by the said wrapper and having a finger grasping portion lying between a 65 wall of the box or container and the wrapper, said finger grasping portion being accessible only upon rupture of that portion of the wrapper adjacent thereto.

The invention comprises other more or 70 less important features as will appear upon a reading of the detailed description to follow when taken in connection with the accompanying drawing which is illustrative of one form of the invention and wherein,

75 Figure 1, is a perspective view of a complete package made in accordance with the invention. Fig. 2, is an end elevation of such a package, the opening device being shown in dotted lines. Fig. 3, is a perspective view of a package showing the opening device partially withdrawn as in the act of severing the wrapper. Fig. 4, is a similar view showing the wrapper completely severed, and Fig. 5, is an elevation of one form 80 of severing device detached from the package.

85 The box or container which contains merchandise may be of any desired construction. In the present instance, I have shown a box 90 or container of common form and which has a movable cover flap 10 provided with the usual flange 12, which, when the box is closed, enters the same and lies parallel with a wall thereof, as for instance, the front 95 wall. The type of box or container herein shown is only by way of illustration and obviously other forms of boxes or cartons may be employed.

100 The box or container is completely enveloped and sealed by means of an inclosing wrapper 13 which incloses all the exterior walls of the box and which wrapper may be adherently attached to all of the said exterior walls of the box, or the wrapper may, 105 when applied to the box or container, be

adherently attached to the overlapping portions of the wrapper or to some of the walls of the box and to portions of the wrapper.

I prefer to employ a wrapper made from 5 a single blank consisting of a body portion and side and end wings, one of the wings having an integral top covering flap having the same dimensions as the body portion of the blank and which top covering flap preferably overlies the movable cover 10 of the box. Such a wrapper blank is shown and described in the allowed application for patent of Henry G. Schwerdtle, Serial No. 810,421, filed January 5, 1914, and is not 15 specifically claimed herein except when employed in association with my improved arrangement of opening device now to be described.

One form of opening device which I prefer to employ is illustrated in detail in Fig. 20 5 and consists of a strip of cardboard or similar material 14 having downwardly inclined or beveled severing edges 15 and a centrally arranged finger grasping portion 25 16 in the shape of a tab or tongue.

After the box or container has been filled with the commodity to be sold and the cover placed thereon, the opening device is inserted down into the box between the flange 30 12 and the adjacent wall of the box, or the opening device may if desired simply rest upon a wall of the box as for instance the front wall with the finger grasping portion extending beyond the wall of the box at right 35 angles to the wall upon which the opening device lies. The wrapper blank 13 is then applied to the box to completely cover all the exterior walls thereof, the blank being so applied as to completely seal the box and 40 completely inclose all portions of the opening device, including the finger grasping portion 16 which, during the covering operation, is folded over upon a wall of the box, preferably the movable wall 10 so that 45 the said finger portion will lie between a wall of the box and a portion of the wrapper blank, no openings of any kind being left in the wrapper. The box or container is therefore completely sealed and effectively 50 excludes air, moisture and vermin.

I prefer to provide the wrapper blank at the point where it covers the finger grasping portion 16 of the opening device with an indicating mark of some kind, preferably 55 a line, as 17, Fig. 1, bounding the finger grasping portion 16 to indicate where the finger grasping portion lies. Such an indicating mark is not absolutely essential in all cases, as obviously if the wrapper blank is 60 made of transparent material, such as gla- cine paper, the finger grasping portion 16 may be seen through the wrapper and an indicating mark therefore, in such instances, is not necessary.

65 When it is desired to open the package,

the portion of the wrapper adjacent the finger grasping portion is broken and the finger grasping portion grasped and withdrawn from the box, the withdrawing operation severing the wrapper along the line 70 of the free end of the movable cover 10 of the box, as more clearly illustrated in Fig. 3, whereupon the remaining sealed portions of the wrapper along the edges of the cover member arranged at right angles to the 75 severed portion of the wrapper may be readily severed by lifting up the cover member, as shown in Fig. 4.

By employing a wrapper blank having a body portion and integral side and end 80 wings for covering the body and side and end walls of the box and an integral top covering flap for covering the top of the box, the box may be readily wrapped and the finger grasping portion 16 turned over 85 flat upon the cover wall of the box simultaneously with the application of the top covering flap 18 of the wrapper blank, since the application of the top covering flap of the blank is the last step in the covering 90 operation of the box, especially when the box is covered by machinery.

Inasmuch as the opening device is completely inclosed within the box and its wrapper, with no parts projecting, the package 95 will be completely sealed, no openings or crevices being left for the entrance of air, moisture or vermin, and this, I consider, of prime importance.

I do not wish to be understood as limiting myself to the particular form of opening device herein shown and described as other forms of such devices may be employed without departing from the spirit of the invention, the essential feature of 100 which is to provide a sealed wrapped package 105 with an opening device having a grasping portion, the said opening device being completely inclosed within the wrapper of the package, but a portion of which may be 110 readily grasped for withdrawal purposes to sever the wrapper when desired.

What I claim is:

1. A sealed wrapped package, comprising 115 a box and a wrapper completely enveloping all the exterior walls thereof and sealing the same, and a wrapper-severing device completely inclosed by the said wrapper and having a finger-grasping portion lying between a wall of the box and the wrapper, 120 said finger-grasping portion being accessible only upon rupture of that portion of the wrapper adjacent the same.

2. A sealed wrapped package, comprising 125 a box and a wrapper completely enveloping all the exterior walls thereof and sealing the same, and a wrapper-severing device completely inclosed by the said wrapper and having a finger-grasping portion lying between a wall of the box and the wrapper, 130

said finger-grasping portion being accessible only upon rupture of that portion of the wrapper adjacent the same, and the said wrapper having a suitable mark indicating 5 the position of the said finger-grasping portion.

In testimony whereof I have hereunto set

my hand in presence of two subscribing witnesses.

JOHN STOGDELL STOKES.
